ALBERT RAKESTRAW, OF PEORIA, ILLINOIS.

Letters Patent No. 79,257, dated June 23, 1868.

IMPROVED CHERRY-STONER.

The Schedule referred to in these Letters Patent and making part of the same.

TO ALL WHOM IT MAY CONCERN:

Be it known that I, ALBERT RAKESTRAW, of Peoria, in the county of Peoria, and State of Illinois, have invented a new and valuable Improvement in Cherry-Stoners; and I do hereby declare that the following is a full, clear, and exact description of the construction and operation of the same, reference being had to the annexed drawings, making a part of this specification, and to the letters and figures of reference marked thereon.

Figure 1 of the drawings is a longitudinal sectional view of my device, and
Figure 2 is a plan view thereof.

The object of my invention is to provide better means than have heretofore been devised for removing the stones or pits from cherries.

Letter A of the drawings represents a hopper in which the cherries are placed for stoning. It is adjusted to the top of the frame on an angle of about eighty degrees, for the purpose of allowing the cherries to roll gradually therein down to the opening B.

Letter C is an opening in the sliding bar D.

Letter E is a similar opening in the stationary top piece of the frame. Each of these openings last named corresponds in size with the opening B, and in conjunction therewith is designed to convey the cherries to the box F.

Letters G and H are openings in the base-board of the frame, and

Letters I and K are openings in the ends of the box F.

The letter L, on the sliding bar D, is a pin that moves in a slot on the lower side of hopper A, and operates as a stop to prevent said bar from passing beyond the point desired. This stop is effected when the pin L is crowded against the extreme end of said slot, at the point M.

The letter O is a fork, composed of four tines usually, so adjusted and arranged as to leave sufficient space between them to hold a single cherry securely.

Letter P is a rod extending from the fork O to the movable block Q, with both of which it is connected.

Letter R is a rod extending from the block Q to the sliding bar D, and uniting the same.

Letter S is a spring adjusted in the manner shown, the office of which is to return the block Q and its attachments to their proper places after the same have been pushed forward.

My device is operated as follows, namely: I fill the hopper with cherries, and force the block Q forward until the pin L rests against the shoulder M of the hopper-slot. The spring S then aids me to return the block as above mentioned. This movement is all that is required, for the beam D and fork O are carried forward at the same time, and as the opening C reaches the opening E, the cherries fall through them into the box F, where they are caught by the fork and carried to the opening K, in which the stone is forced outward through opening H. The pulp of the cherry remains in the fork, and is released therefrom by the shoulders of opening I, and passes downward through opening G.

What I claim as my invention, and desire to secure by Letters Patent, is—

A cherry-stoner having sliding-beam D, openings B, C, E, H, and K, fork O, and block Q, constructed, arranged, and operating substantially as herein specified.
